UNITED STATES PATENT OFFICE

2,282,013

AIR CONDITIONING SYSTEM

Raymond V. Wetstone, Butte, Mont.

Application November 15, 1939, Serial No. 364,625

6 Claims. (Cl. 237—8)

This invention relates to air conditioning systems, and particularly to air conditioning units of the type in which room air is passed through a treating chamber or unit and then returned to the room.

The invention may be incorporated in apparatus of any desired size but is particularly useful in the case of relatively small capacity installations for dwellings, stores and theatres. An objection to many of the present small air conditioning systems is the failure to maintain the desired room temperature when the demand for heat is well below the maximum capacity of the conditioning unit. The prior "on-off" control systems resulted in an intermittent operation of the conditioning unit and the room temperature would overrun each time the conditioning unit was turned off. The interruptions of the air conditioning action were particularly objectionable when, as was customary, the air circulating fan was stopped when the room temperature was at or above the desired control point.

One object of the present invention is to provide an air conditioning system of the separate conditioning unit type that includes control devices for regulating the supply of heating or cooling fluid to the conditioning unit in accordance with the existing demand. An object is to provide an air conditioning system including a treating chamber, a heating coil in the treating chamber, a fan for passing room air through the chamber and returning it to the room, a control system for regulating the heat supply to the coil in accordance with the demand for heat in the room, and an additional control to prevent operation of the circulating fan when the coil temperature is too low to supply heat to the circulating air stream. A further object is to provide an air conditioning system including a conditioning unit having a heating coil with a supply connection to a hot water boiler, a water circulating pump and return connection from the coil to the boiler, a by-pass from the return connection to the supply connection, and a three-way modulating valve under control of room temperature for regulating the relative quantities of boiler water and of recirculated water that are supplied to the heating coil. Another object is to provide an air conditioning system, of the type last stated, in which the circulating pump and the hot water boiler have a control system that is energized by the modulating valve when the latter is adjusted, in response to the room thermostat, to supply heated water from the boiler to the conditioning unit coil.

These and other objects and advantages of the invention will be apparent from the following specification when taken with the accompanying drawing, in which:

5 Fig. 1 is a schematic view of an embodiment of the invention; and

Fig. 2 is a fragmentary schematic view of an alternative control system for the air circulating fan and the humidifier.

10 In the drawing, the reference numeral 1 identifies the space or room for which the air is to be conditioned by treatment in a chamber 2 that is connected to the room 1 by an inlet passage 3 and return passage 4. A circulating fan 5 is located 15 in the conditioning chamber, or one of the passages, and its motor 6 may be within the path of the air stream or, as illustrated, at the exterior of the air passages and chamber. A humidifier 8, preferably of the spray nozzle type, is located 20 in the chamber beyond the heat exchanger 2 and is controlled by an electrically operated valve 9. The heat exchanger is connected to a hot water boiler 10 by a supply conduit 11 and return conduit 12 that includes a circulating pump 13 and check valve 14. A by-pass conduit 15 extends from the return conduit 12, at a point between the pump 13 and check valve 14, to the three-way modulating valve 16 in the supply line 11. As shown in Fig. 1, the valve 16 is positioned 25 to open the conduit 11 and close the by-pass 15. The entire input to the heat exchanger is therefore the high temperature water from the boiler. Clockwise adjustment of the valve 16 effects a progressive opening of the by-pass 15 and a progressive throttling of the hot water inlet to the valve.

30 The modulating valve 16 is adjusted by a reversible motor 17 that is controlled, in known manner, by a modulating thermostat T in the room 1, and a bridge network and balanced relay, not shown in detail, in the box 18. The motor and the bridge network of this modulating control system are energized from an alternating current power line 19 through the transformer 20.

35 The supply of fuel to the boiler 10 is controlled automatically but the particular type of fuel is not important as automatic controls are known for boilers of the gas, oil or coal fired type. For simplicity of illustration, a fuel supply conduit 21 under control of an electrical device 22 is shown in Fig. 1. The circuit of the control device 22 includes a transformer 23 that is connected across leads 24, and a temperature-controlled switch 25 that responds to the temperature of the water within the boiler 10. The switch 25

may be a normally closed "high limit" switch that opens when the water temperature exceeds a selected value, or a normally open "low limit" switch that closes to complete the energizing circuit for the device 22 when the water temperature drops below a selected value.

The exact design of the fuel control system will depend upon the particular type of commercial boiler that is used; the control of the boiler operation being determined primarily by the relay operated switch 28 that is located between the controlled leads 24 and the power line 19. The solenoid of the switch 28 is connected across the secondary winding of the transformer 20 by leads 27 and a switch 28 that is actuated to closed position by the motor 17 when the modulating valve 16 is adjusted to open, or partially open, the supply conduit 11 to the heat exchanger 1 of the conditioning chamber. The controlled circuit leads 24 supply energy to the motor 29 of the water circulating pump 13 and, through a temperature-controlled switch 36, to the fan motor 6 and to the transformer 31 of the humidity control circuit that includes the electrically operated valve 9 and a room humidistat H. The actuating element of the switch 30 is located in the return conduit 12, and adjacent the heat exchanger 1; the switch 30 being so adjusted that it does not close until the treating chamber temperature, as reflected in the exit temperature of 30 the circulated heating fluid, rises to a selected value.

For cooling in summer, the cold water inlet pipe 11' and exhaust pipe 12' are connected to the conduits 11, 12, respectively, and manually operable valves 33 are included in conduits 11, 12 and pipes 11', 12' for connecting the appropriate fluid supply system to the heat exchanger 2. The cold water pipe 11' may extend to a deep well or to a refrigerator system.

The operation of the system is as follows. Assuming that the thermostat T has just been adjusted, either manually or by known clock mechanism, from a night temperature of 50° to a day temperature of 70°. This change in the setting of the thermostat T results in an energization of the motor 17 to move the modulating valve 16 into the fully open position shown in Fig. 1, and also closes the relay switch 28 to connect the controlled leads 24 to the power line 19. The water circulating pump 13 is thus placed in operation and the furnace controls are energized. The fan 5 and humidifier 8 are not placed in operation until the return water temperature rises to such a value that the circulation of air through the room 1 will not produce cold drafts.

The room temperature rises as soon as the fan 5 is in operation and, as the temperature approaches the desired control point, the motor 17 is brought into operation by the modulating thermostat T to move the modulating valve 16 clockwise. This results in the recirculation of a part of the return water from the heat exchanger and thus lowers the rate of heat supply to the conditioning chamber. The supply of heat to 65 the room 1 thus decreases progressively as the room temperature approaches the selected control point. The air conditioning system will thus remain in continuous operation for long periods under normal conditions and the tendency towards overrunning of the temperature is substantially eliminated.

As shown in Fig. 2, the operation of the fan motor 6 and the energization of the humidity control circuit 32 may be directly responsive to 75

the air temperature within the conditioning chamber 2. This form of control circuit includes a thermostatic member such as a Sylphon bellows 30a within the chamber 2 for operating a mercury switch 30b to closed circuit position when the chamber temperature rises to a selected value that will prevent cold drafts.

For summer cooling, the valves 33 are adjusted to connect the cold water pipe system 11', 12' to the heat exchanger, and the furnace control circuit is opened manually. A cooling thermostat operates through relays to turn on the air circulating fan at say 78° and to start a pump in the cooling water system at say 80°. If desired, the exit cold water pipe 12' may be connected to the hot water return pipe 12 between the check valve 14 and the boiler 10, thus permitting a control of the rate of cooling by the modulating valve 16.

It is to be understood that the invention is not limited to the particular constructions herein shown and described as different parts of the control system may be modified, if necessary or desirable, in accordance with the particular structure of the boiler and its type of control. The boiler control device 22 may be an electromagnetic valve when the fuel is gas, or a motor when oil or coal is used.

I claim:

1. In an air conditioning system, the combination with a conditioning chamber, a heat exchanger within the chamber, and passages connecting said chamber with a room for which the air is to be conditioned, of a fan for establishing a flow of air from said room through the conditioning chamber and back to the room, a hot water boiler, supply and return conduits connecting said heat exchanger to the boiler, a circulating pump in one of said connections, means including a modulating valve in the supply conduit and a thermostat in the room for regulating the rate of heat supply from the boiler to the heat exchanger in accordance with the room temperature, and an electrical control system for said fan and said pump, said control system including a switch actuated by said modulating valve.

2. In an air conditioning system, the invention as claimed in claim 1, wherein said modulating valve is a three-way valve, and a by-pass conduit extends from said valve to the return conduit, whereby water from said heat exchanger may be mixed with hot water from the boiler and returned to the heat exchanger.

3. In an air conditioning system, a conditioning chamber, a heat exchanger within said chamber, a fan for establishing a stream of air through said chamber and into the space for which the air is to be conditioned, means controlled by temperature changes within said space for supplying to said heat exchanger hot water at a temperature that varies with the departure of the space temperature from a preselected value, and a control circuit for said fan including a switch for delaying the energization of said fan until the temperature within said conditioning chamber reaches a preselected value.

4. In an air conditioning system, the invention as claimed in claim 3, wherein said switch includes an operating member subject to the temperature of the water leaving said heat exchanger.

5. In an air conditioning system, the invention as claimed in claim 3, wherein said switch includes an operating member subject to the tem-

perature of the air within said conditioning chamber.

6. In an air conditioning system, the combination with a heat exchanger, a hot water boiler, conduits connecting said heat exchanger and boiler, and a pump in one of said conduits for circulating water from the boiler through said heat exchanger, of means for adjusting the flow of water from the boiler to the heat ex-

changer, said means including a modulating valve in one of said conduits and a by-pass extending from said valve to the other conduit, a thermostat in the space to be heated for actuating said modulating valve, and relay means including a switch actuated by said modulating valve for energizing said pump and controlling the fuel supply to said boiler.

RAYMOND V. WETZSTEON.
